CLAIM

The ornamental design for a cervical visualization harness, as shown and described.

DESCRIPTION

FIG. 1 is an environmental perspective view of a cervical visualization harness showing my new design;
FIG. 2 is a front elevational view thereof;
FIG. 3 is a rear elevational view thereof;
FIG. 4 is a top view thereof;
FIG. 5 is a right side elevational view with the left side being a mirror image thereof; and,
FIG. 6 is a bottom view thereof.
The broken line showing of the patient and the operating table is for illustrative purposes only and forms no part of the claimed design.

FIG.1

FIG. 2

FIG. 3

FIG. 5

FIG. 4

FIG. 6
